UNITED STATES PATENT OFFICE.

ALFRED JOHNSON, OF BROOKLYN, NEW YORK.

AUTOMATIC SASH-LOCK.

SPECIFICATION forming part of Letters Patent No. 769,386, dated September 6, 1904.

Application filed March 9, 1904. Serial No. 197,209. (No model.)

To all whom it may concern:

Be it known that I, ALFRED JOHNSON, a citizen of the United States, residing at Brooklyn, in the county of Kings and State of New York, have invented certain new and useful Improvements in Automatic Sash-Locks, of which the following is a specification, such as will enable those skilled in the art to which it appertains to make and use the same.

The object of this invention is to provide an improved lock for the sashes of windows whereby the sashes will be securely locked together when in a closed position; and with this and other objects in view the invention consists in a device of the class specified constructed as hereinafter described and claimed.

The invention is fully disclosed in the following specification, of which the accompanying drawings form a part, in which the separate parts of my improvement are designated by suitable reference characters in each of the views, and in which—

Figure 1 is a front view of a window the sashes of which are provided with my improved lock; Fig. 2, a section of a part of the upper sash; Fig. 3, a front view thereof; Fig. 4, a section on the line 4-4 of Fig. 1, but showing the sashes unlocked; Fig. 5, a view similar to Fig. 4, but showing the sashes locked together; Fig. 6, a bottom plan view of that part of the sash-lock which is connected with the lower sash, part of the construction being broken away and part shown in section; Fig. 7, a view similar to Fig. 6, but showing the parts in a different position; and Fig. 8, a plan view of that part of the lock shown in Fig. 6.

Figs. 2 to 8, inclusive, of the accompanying drawings are made full size and on a scale larger than Fig. 1, and in said drawings I have shown at *a* an ordinary window-frame having upper and lower sashes *a*² and *a*³, and in the practice of my invention I provide a sash-lock composing a part *b*, which is secured to the bottom rail of the upper sash, and a part *c*, which is secured to the top rail of the lower sash.

In the accompanying drawings the bottom rail of the upper sash is provided with a cleat or strip *a*⁴, which aids in holding the glass *a*⁵

in position, and the top rail of the lower sash is provided with a cleat or strip *a*⁶, which aids in holding the glass *a*⁷ in position; but this construction is not absolutely necessary, and any suitable means may be provided for holding the glasses *a*⁵ and *a*⁷ in their respective sashes.

The part *b* of my improved sash-lock which is secured to the bottom rail of the upper sash *a*² is open at the front and closed at the back, said back being segmental in horizontal section and is provided with a top portion *b*¹, having a depending lip *b*², and within the right-hand portion thereof is an inclined shoulder or projection *b*³, the front side of which is inclined downwardly and forwardly, and said part *b* is also provided with side projections *b*⁴, whereby it may be secured to the bottom rail of the upper sash, as shown in Fig. 2.

In constructing the part *c* of my improved sash-lock, which is secured to the top rail of the lower sash, I provide a casing *c*¹, which is hollow and the front part of which is segmental in form, and said casing *c*¹ is provided with a top plate *c*² and with side extensions *c*³, whereby it may be secured to the top rail of the bottom sash. The top plate *c*² of the casing *c* is provided with a central opening *c*⁴, and mounted on said casing *c* is a lock-plate *d*, having a laterally-directed handle *d*¹. The lock-plate *d* is segmental in form at one side and provided with a flange *d*², which extends about two-thirds of the way around the same, and said lock-plate is held in place by a screw or bolt *d*³, which passes downwardly through said plate and to the bottom end of which is secured a plate *e*, part of which is shown in section in Fig. 5, and the end portions only of which are shown in Figs. 6 and 7, and said plate *e* constitutes a bottom for the casing *c*¹.

The lock-plate *d* is also provided centrally thereof with a tubular journal *d*⁴, which passes downwardly through the opening *c*⁴ in the top plate *c*² of the casing *c*¹, and in one side of the lower end of the tubular journal *d*⁴ is a recess *d*⁵. The plate *e* is also provided centrally of the upper side thereof with a sleeve *e*¹, which passes upwardly into the journal *d*⁴, and wound on the screw or bolt *d*³ is a spring *f*, one end

of which is secured to the plate d or to the journal d^5 , and the other end of which is connected with the sleeve e^2 by being passed out through a slot e^3 , formed therein, or in any desired manner. The top plate c^3 of the casing c^2 is also preferably provided with a segmental bearing g , in which the journal d^5 turns, and in the front portion of the casing c^2 and pivoted to the top plate c^3 thereof by means of a screw or similar device g^2 is a dog g^3 , having a nose g^4 , which is adapted to enter the recess d^6 in the journal d^5 , and pivoted to said dog g^3 is an arm g^5 , which passes backwardly through the back wall of the casing c^2 and which is shown in its innermost position in Fig. 7 and in its outermost position in Fig. 6, and said dog is normally held in the position shown in Fig. 6 by a spring g^6 , coiled on the pivot-screw g^2 , and one end of which bears on the casing c^2 and the other of which is connected with said dog, as shown at g^7 .

The normal position of the lock-plate d when the sashes are not locked together is that shown in Fig. 4, in which position the handle d^2 is turned to the right, and the normal position of said plate when the sashes are locked together is that shown in Fig. 5, in which the handle d^2 is turned to the left, as shown in full lines in Figs. 7 and 8. Suppose the parts to be in the position shown in Fig. 4. In this position the dog g^3 and the journal d^5 are in the position shown in Fig. 6. If now the upper sash be raised or the lower sash lowered, the arm g^5 will be forced backwardly by the inclined shoulder or projection b^4 , and this will release the dog g^3 from the journal d^5 and all the parts will assume the position shown in Fig. 7, and the flange d^3 of the plate d will engage the lip b^3 at the top of the casing b and the sashes will be securely locked together. In order to disconnect the sashes, the plate d is turned by means of the handle d^2 to the right, as shown in Fig. 4 and in full lines in Fig. 8 and also in full lines in Fig. 6, and the upper sash may be lowered or the lower sash raised, as may be desired, and in order to lock the sashes together the above-described operation is repeated.

Although I have described the journal d^5 as tubular in form, the interior thereof in the form of construction shown is angular in cross-section, as clearly shown in Figs. 6 and 7, and in securing the spring f as hereinbefore described the upper end thereof is connected with a plate h and is placed in the top portion

of said journal, and this plate turns with the lock-plate d and the effect is the same as though the spring were secured to said lock-plate directly or to the journal d^5 . 60

My improved sash-lock is simple in construction and automatic in operation, and changes in and modifications of the construction described may be made without departing from the spirit of my invention or sacrificing its advantages. 65

Having fully described my invention, what I claim as new, and desire to secure by Letters Patent, is—

A window-sash lock comprising two parts, 70 one of which is adapted to be secured to the bottom portion of the upper sash and the other to the top portion of the lower sash, that part which is adapted to be secured to the bottom portion of the upper sash comprising a casing 75 open at the front and having a depending top lip and an inclined lug or projection, and that part which is adapted to be secured to the top portion of the lower sash comprising a casing having a top opening, a locking-plate mounted 80 thereon and provided with a tubular journal which passes downwardly through said opening and is provided in one side with a recess, said casing being also provided with a bottom plate having a tubular sleeve adapted to enter 85 said journal, a spring mounted in said sleeve and journal and one end of which is secured to the locking-plate and the other to said sleeve, a spring-operated dog mounted in said casing and adapted to engage the recess in said journal, and an arm connected with said dog and passing backwardly through said casing and adapted to be operated by the inclined lug or projection in that part of the device which is adapted to be connected with the upper sash, 90 said locking-plate being also provided with a segmental and inclined flange or rim adapted to engage the lip of that part of the device which is adapted to be connected with the upper sash, and said locking-plate being also pivoted at one side of the casing which is adapted to be connected with the lower sash and provided at the opposite side with a handle, 95 substantially as shown and described.

In testimony that I claim the foregoing as 100 my invention I have signed my name in presence of the subscribing witnesses.

ALFRED JOHNSON.
